UNITED STATES PATENT OFFICE.

GEORGE LAWSON BALLARD, OF NORRISTOWN, PENNSYLVANIA, ASSIGNOR TO
WILDMAN MFG. CO., A CORPORATION OF PENNSYLVANIA.

CIRCULAR-KNITTING MACHINE FOR MAKING NECKTIES AND THE LIKE.

1,200,451.

Specification of Letters Patent. Patented Oct. 10, 1916.

Application filed May 22, 1914. Serial No. 840,377.

To all whom it may concern:

Be it known that I, GEORGE L. BALLARD, a subject of the King of Great Britain, residing at Norristown, Pennsylvania, have 5 invented certain new and useful Improvements in Circular-Knitting Machines for Making Neckties and the like, of which the following is a specification.

It is the object of my invention to provide 10 a circular knitting machine adapted to make variations in the pattern of a tubular fabric, such for instance in making knitted neckties.

It comprises a pattern drum or mechanism 15 connected with needles forming a part or the whole of the needle circle, and adapted to control said needles, to knit plain fabric, or to perform variations in the knitting as by making tuck stitches at desired points 20 to make the pattern.

While my invention may be embodied in various forms and with pattern needles constituting more or less of the needle circle, in the particular machine shown the pattern 25 needles occupy about one-fourth of the needle circle, these needles being controlled from the pattern drum.

In the accompanying drawings Figure 1 is a central vertical sectional view of the 30 machine with parts in elevation; Fig. 2 is a plan view in the nature of a diagram; Fig. 3 is a side view of the machine looking from the left of Fig. 1; Fig. 4 is a development of the cams of the rotary cam ring for 35 the cylinder needles; Fig. 5 is a detail view of one of the pattern pins; Fig. 6 is a view of a detail.

When the machine is organized with pattern needles forming only a part of the 40 needle circle, two sets of needles are employed, one set *a* with long stems and the other set *b* with short stems. The long stem needles are operated by a lower set or circle of cams 1 in the revolving cam ring 2, while 45 the short stem needles are controlled by the upper set or circle of cams 1^x. The machine has multiple feeds. In the present instance I employ two feeds, as is indicated by the fact that I show in Fig. 4 two sets of cams 50 for each set of needles. The pattern needles are controlled either to knit or tuck, and thus make the pattern for the front of the necktie or tubular fabric, and for controlling these needles the advancing cams there-

for are made of two heights each indicated 55 at 3, 4, the portion 3 being one-half approximately of the thickness of the cam ring, and occupying the inner half, while the portion 4 constitutes the outer half of the cam ring.

The long stem pattern needles are adapted 60 to occupy either one of two positions at different distances radially in relation to the center of the machine, and consequently to the cam ring, so that their butts 5 will ride either upon the advancing cam portions 65 3 or upon the advancing cam portions 4 in the former case, *i. e.*, when they are deep in their grooves to cause their butts to ride upon the low cam portion 3, these pattern needles will tuck due to the needle being 70 advanced only high enough to take the yarn but without moving the latch above the old loop, while when the said pattern needles are adjusted to their outermost positions in the cylinder grooves, the needle butts of 75 these pattern needles will ride upon the high part 4 of the advancing cams and then these needles will knit. The short stem needles forming the remainder of the needle circle will knit, they engaging the upper cam 80 groove and working in the regular way independently to form with the dial needles plain rib stitch for the back portion of the fabric, and along the edges of the front of the tie if such design is desired, these 85 needles, in the particular instance now being described as an example of my invention, forming plain rib fabric for more than one-half of the tube.

The pattern needles are held in their innermost position in the cylinder grooves by 90 the intermediate bent portions bearing on the inner side of the cam ring. They are shifted individually outward to make their butts ride up the high parts 4 of the advancing cams by the sliding pushers or 95 needle shifters or adjusters 6 arranged in recesses or grooves 7 at the lower part of the needle cylinder, and communicating with the regular needle grooves. These pushers 100 or needle shifters are operated vertically in their grooves by links 8 pivoted to the lower ends of the pushers and pivotally connected at their other ends to pattern levers 8' pivotally mounted individually on a rod 9 supported in a frame part or bracket 10. The 105 needle shifters are provided with inclined or curved inner upper edges at 11 bearing on

the correspondingly inclined or curved bottoms of the upper ends of the grooves in which the pushers slide.

The outer edges of the pushers or needle shifters are vertical, conforming to the substantially vertical inner edges of the needle stems. When any needle adjuster or pusher is elevated by the pattern mechanism, the needle controlled thereby will be shifted radially outwardly by the pusher, which is itself shifted outwardly by its inclined or curved upper end working on the inclined upper portion of its groove, the parts maintaining, however, their vertical positions.

Any needle or number of needles of the pattern set may be controlled to knit, while other needles of said pattern set may be controlled to tuck, and thus produce the pattern when different colored yarns are used at the two feeds. When knitting that portion of the tube which does not form the pattern front of the tube or tie, all the pattern needles may be controlled to knit, or in making the neck band of the tie all the needles of the pattern set will knit, thus forming, together with the short stem needles, plain rib for the neck band.

The pattern levers 8' are controlled by pins 12 of a pattern drum 13, said pins having cylindrical shanks held frictionally within holes 14 of the said drum. These pins have rectangular heads 15 to operate on the arms 16 of the pattern levers. The pattern drum is operated step by step by a ratchet wheel 17 fixed thereto, and a pawl 18 on a lever 19 hung on the axis of the pattern drum, said lever having a forked end 20 operated by a crank or eccentric on a shaft 21. This shaft is driven through gearing 22 from the shaft of the bevel gear 23 which drives the cam ring by meshing with the bevel gear 24. The pattern drum shaft is journaled in a bracket 25 secured to and depending from the base 26 of the machine. The pattern levers 8 are pressed by springs 27 which hold them to their work against the pattern drum, these springs being carried by the levers and bearing on a plate 27' fixed to the bracket.

For controlling the levers 8' a detent plate 28 is employed. This is provided with a number of spring fingers at its upper part formed by making vertical cuts or slits in the plate extending from its upper edge downwardly, so that there is a spring finger for each of the levers 8'. The detent plate 28 is carried by a cross bar 29 attached to an arm 30, the end of which is supported slidably by a pin and slot at 31. This arm is operated at the proper time to move the retaining plate or comb under the elevated ends of the pattern levers by an arm 32 depending from a shaft 33 and connected pivotally to the arm 30, said shaft having its bearings in a bracket 34 on the under side of

the base plate. The shaft 33 is rocked by an arm 35 from a pattern wheel 36 suitably mounted and driven. When the needles *a* are knitting the pattern, each one assumes positions suitable for forming the pattern desired, for instance, they will assume positions alternately for knitting and tucking; that is, knitting on one feed and tucking on the other feed.

The movement of the drum is timed to act in the space between the two raising cams 4, 4, and therefore in the particular construction shown the pin drum would be operated twice for each revolution of the machine. When all the pattern needles are to be maintained in their outward position to engage the high cam part 4 for knitting, the detent plate 28 is pressed by its carrier 30 leftward, so that as the needle pushers or adjusters 6 are lifted by successive actions, *i. e.*, part 80 of the series being lifted at one action of the drum and part at another action, the detent fingers will spring under the raised pattern levers 8' and hold them together with their pushers up and the needles so held up will knit. The spring detents will yield when, on their leftward movement, they strike the ends of those pattern levers which have not yet been lifted, and they will thus be in position to spring under the end of the 95 levers 8' when they are raised.

This machine, in some of its aspects, is similar to that disclosed in an application for Letters Patent of the United States filed by F. B. Wildman, #704,440, dated June 100 18, 1912, (Patent No. 1,167,866, Jan. 11, 1916); that is, long and short stem needles are used and two circles of needle operating cams in the cylinder cam ring, each circle of cams being adapted for a multiple feed 105 machine, by which the needles may be controlled to either knit or tuck. As in said machine the present machine would be equipped with suitable yarn changers or strippers to change the color of yarn used. 110 These yarn changers may be of any suitable form, as in said application, or of other forms, and they may be operated in a manner such as in said application.

The cylinder cam ring in the present case 115 includes two circles of needle cams, the upper circle 1*, as shown in Fig. 4, having its cams to operate with multiple yarn feeds, the advancing cams being indicated at *x* and *y* and the stitch cams at *x'* and *y'*. This set 120 of cams operates the short stem needles *b*. The lower circle of cams 1 operates the long stem needles as above described, and comprises besides the two advancing cams 3, 4, 3, 4, the stitch cams *z*, *z'*. The upper advancing cam *y* is adjustable vertically for knitting or tucking on the short stem needles, and by adjusting this cam down to the position shown in dotted lines in Fig. 4 all the short stem needles will tuck on this

- feed, whereas the short stem needles will all knit at the other feed because the cam α at this feed remains up to advance all these short stem needles high enough for knitting.
- 5 The cam γ is adjusted up on one revolution to knit and down on the next revolution to tuck, and accordion fabric will thus be formed on the short stem needles, and if there is more than a half circle of these 10 short stem needles this character of fabric will be knit at the back and side edges of the tie or tube. For adjusting the advancing cam γ into either its knitting or tucking position, mechanism similar to that disclosed 15 in the above mentioned application of Wildman is employed, consisting of a cam block 37 to engage a pin 38 extending from the post 39 to which the cam γ is secured, said cam block 37 being fixed to a ring 46 movable circumferentially about the knitting head. This ring is operated by arms 40, 41, connected with shafts 42, 43, mounted in the cam ring and connected together by gearing 44, as is usual in the Wildman type of rotary cam machine. The arms 40 and 41 are operated by a tappet roller 45 mounted on the fixed base of the knitting head, said roller being adjusted vertically by pattern mechanism into line with the arm 40 or the 25 arm 41. This pattern mechanism may be of any suitable form. Its action, together with that of the tappet roller 45, is well known in the Wildman type of machine. The arm 40 is connected to the ring 46 by a pin 47 on 30 said arm engaging a grooved block 48 fixed on the ring 46.
- It will be understood that with the mechanism above described the needles may be operated in various orders to produce a great 40 variety of patterns.
- I claim as my invention:—
1. In a circular knitting machine, a fixed needle cylinder, two groups of needles, the needles of one group occupying one segment 45 of the needle circle and the needles of the other group occupying another segment of the needle circle, one group of needles having long stems and the other group short stems, a set of cams for the long stem needles having a high and a low needle path, means 50 for adjusting the long stem needles individually and selectively to be operated by either the high or low path so that the needles of this segment may tuck or knit in any desired order, and a set of cams for the 55 short stem needles which occupy the other segment of the needle circle, substantially as described.
  2. In a circular knitting machine, a fixed 60 needle cylinder, two groups of needles, the needles of one group occupying one segment of the needle circle and the needles of the other group occupying another segment of the needle circle, one group of needles having long stems and the other group short 65
- stems, a set of cams for the long stem needles having a high and a low needle path, means for adjusting the long stem needles individually and selectively to be operated by either the high or low path, so that the 70 needles of this segment may tuck or knit in any desired order, and a set of cams for the short stem needles which occupy the other segment of the needle circle, said cams for the short stem needles including an advancing cam with pattern controlled means for adjusting said cam to tuck, substantially as described.
3. In combination in a circular knitting machine, a needle cylinder, a set of long 80 stem needles, a set of short stem needles, a set of needle cams for the long stem needles including an advancing cam having high and low cam paths for advancing the long stem needles for knitting and tucking respectively, a set of shifters for the long stem needles for effecting radial movement of the long stem needles to be operated either by the high or the low cam path, pattern mechanism controlling the said shifters to select 85 and adjust said long stem needles individually, a set of needle cams for the short stem needles, including a vertically adjustable advancing cam to advance the short stem needles for knitting or tucking, and 90 pattern controlled means for operating the said advancing cam, said pattern controlled means including tappet operated connections carried by the cylinder cam ring, substantially as described. 100
4. In combination in a circular knitting machine, a needle cylinder, needles, needle cams, a series of shifters for effecting movement of the needles radially in relation to the needle cams to be operated thereby for 105 knitting or tucking according to the position to which the needles are adjusted, and pattern mechanism for adjusting the shifters alternately for knitting and tucking, said pattern mechanism including automatically operating means for maintaining the needle shifters in their adjusted position for continued knitting, substantially as described. 110
5. In combination in a circular knitting machine, a needle cylinder, needles, needle cams, including an advancing cam having high and low cam paths for respectively operating the needles for knitting and tucking, a series of needle shifters for effecting 115 radial adjustment of the needles to be operated either by the high or low cam path, a pattern member, connections between said pattern member and the needle shifters for adjusting the needles for knitting or tucking, and a pattern member with detent means controlled thereby for maintaining the needle shifters in position for knitting, thus eliminating for a determined period 120 the changes controlled by the pattern mem- 125
- 65

ber first mentioned, substantially as described.

6. In combination in a circular knitting machine, a needle cylinder, needles, needle cams, a plurality of needle adjusters for setting the needles for either knitting or tucking, a pattern member with connections to the needle adjusters, detent means for engaging and holding said connections in position to which they are adjusted by the said pattern member, and a second pattern member with connections to the said detents for rendering them effective for engaging and holding any one of the connections which may be operated by the first pattern member for setting the needle adjuster, substantially as described.

7. In combination in a circular knitting machine, a needle cylinder, needle cams, needles shiftable radially of the cylinder to engage different parts of the needle cams, a series of adjusters for the needles to effect radial adjustment thereof, a pattern member with a series of connections leading therefrom to the different needle adjusters, a detent plate having a series of yielding detents one for each of said connections, and a pattern member with connections to the detent plate for applying pressure thereto, said detents operating individually upon the needle adjuster connections to maintain any one of them in adjusted position for a predetermined period, substantially as described.

8. In combination a needle cylinder, needle cams, needles shiftable radially to engage different parts of said needle cams,

a series of needle adjusters for effecting radial adjustment of the needles in relation to their cams, a pin drum, a series of levers operated thereby, connections between the said levers and the needle adjusters, a series of detents one for each of the levers, a pattern mechanism for pressing the detents into engagement with the levers, said detents acting to maintain the levers in the position to which they are removed by the pin drum, and means for operating the pin drum step by step, substantially as described.

9. In combination a fixed needle cylinder, a rotary cam ring, long and short stem needles, a set of cams for each set of needles, the needle cams for the long stem needles having an advancing cam with a high and a low cam path, a series of needle adjusters for effecting radial adjustment of the long stem needles to engage either the high or the low cam paths, pattern mechanism arranged at one fixed point and connected with the needle adjusters for operating them individually, the set of needle cams for the short stem needles including a vertically adjustable advancing cam, pattern controlled tappet means, and connections revolving with the cam ring to be actuated by said tappet means for adjusting the advancing cam of the short stem needles, substantially as described.

In testimony whereof, I affix my signature in presence of two witnesses.

GEORGE LAWSON BALLARD.
